RACK

Carl F. Rauen, Grosse Pointe, and Gladys Forhan, Detroit, Mich.

Application April 14, 1941, Serial No. 388,490

2 Claims. (Cl. 45—57)

This invention relates to racks and has particular reference to a small convenient sized rack adapted for general utility for holding articles such as a book, a newspaper, clippings, cards or a sheet of paper in such a manner that printed material thereon is visible to an observer looking downwardly or forwardly thereof.

A principal object of this invention is to provide a device of this character which is more useful and more dependable than devices of this character heretofore available.

Another object of the invention is to provide a rack of the character described which is constructed and arranged in such a manner that articles varying in thickness from a single sheet of paper to a book, and articles as large as a folded newspaper may be arranged thereon so that the printed matter on such articles may be read by an observer either sitting or standing in front of the device.

A device embodying the invention is particularly useful for holding recipes, booklets, clippings, newspapers, memoranda and books in such a position that the printed matter thereon may be conveniently read, the device being constructed and arranged in such a fashion that it can be set up on a table, counter or other surface wherever desired and so that it requires only a relatively small amount of space.

Other objects and advantages of the invention will be apparent from a consideration of the following specification taken in conjunction with the accompanying drawing of which there is one sheet and wherein:

Fig. 1 is a perspective view of one form of device embodying the invention;

Fig. 2 is a vertical section on the line 2—2 of Fig. 1;

Fig. 3 is a rear elevational view; and

Fig. 4 is a section along the line 4—4 of Fig. 1.

As illustrated, a rack embodying a preferred form of the invention consists of a frame member 10, a leg 12 and a clamping or securing spring 14. The frame member 10, as illustrated, may be formed of plastic, sheet metal or any other suitable material and is adapted to stand upon a surface 16 such as the top of a table. The frame member 10 provides a supporting surface for an article of the nature hereinbefore referred to and is of such extent in both directions that it will support a folded newspaper, open book or sheet of paper.

The leg 12 may consist of a piece of wire bent as illustrated and pivotally secured to the rear face of the frame member 10 by brackets 18, the

5 brackets 18 being welded or otherwise suitably secured to the frame member 10 so as to provide a pivotal mounting for the leg 12. Parts 20 of the leg extend upwardly above the pivotal connection between the leg 12 and the frame member 10 so as to provide a stop for the leg 12 so that when the same is opened the frame member 10 will be supported in the position as illustrated in Figs. 1 and 2.

10 The securing or clamping spring 14 comprises a spring steel wire which is bent as illustrated so as to provide a portion 22, bowed-out portions 24, coils 26 and portions 28. The portions 28 are formed as illustrated in Fig. 4 and are each adapted to fit into and cooperate with complementally formed portions of the frame member 10 defined by the slots 30 for mounting the spring 14 upon the frame member 10. The coils 26 are formed about an axis transverse to the line of 15 movement of the portion 22 so as to provide a sort of a pivotal connection between the main part of the spring 14 and the connection between the spring 14 and the frame member 10. That part 28' of the spring 14 adjacent and above the 20 coils 26 is adapted to provide seats for articles clamped to the surface of the frame member 10 and the bowed-out portion 24 of the spring is provided so as to accommodate such articles between the spring 14 and the surface of the plate 25 10. As shown in the drawing, the portion 22 is contacting the surface of the frame member 10 and in operation is adapted to engage the surface of an article and clamp the same against the surface of the frame member 10 in such a manner that printed matter on the article will be visible to an observer looking forwardly or downwardly at the article. The coil 26 and the flexibility of the wire 14 are such as to permit the portion 22 to move away from the surface 10 to a range of at least an inch and a half.

30 The device as shown in Fig. 2 is approximately three-quarter size. The spring 14 is arranged so that there is sufficient pressure between the portion 22 and the surface of the frame member 10 to retain a single sheet of paper against the surface of the frame member 10 and, if desired, the lower edges of the paper may be arranged so as to rest upon the seats 28' provided on the spring 14 adjacent to the coils 26. The portion 22 is, 35 by virtue of the construction of the spring 14, capable of moving away from the surface 10 such a distance so as to support an opened book between the spring 14 and the surface 10, without giving a "set" to the spring.

40 The shape of the spring may be said to be

heart-shaped or U-shaped and the spring is formed as illustrated so that when the portions 28 are arranged in the slots 30, the resiliency of the spring itself will retain the parts 28 in the slots 30. The simplicity of the spring mounting facilitates the assembly of the spring to the frame member 10.

We claim:

1. A rack for holding articles such as a book, a newspaper, clippings, a card or sheet of paper in such a manner that printed matter thereon is visible to an observer looking downwardly or forwardly thereat comprising a frame member providing a laterally extending supporting surface, and means for retaining an article of the nature hereinbefore referred to upon said supporting surface comprising an inverted generally U-shaped spring wire secured to said frame member, an intermediate part of said wire at the upper end thereof forming an apex which is biased into engagement with said frame member in order to contact an article and removably clamp the same to said surface of said frame member, said frame member adjacent each of the lower corners thereof but spaced inwardly from the edges thereof being provided with a U-shaped slot with the tongues formed thereby extending toward each other, each of the ends of said wire being bent so as to extend through one of said slots with a portion of said wire arranged behind and held in place by the tongue of said one of said slots, said ends of said wire being biased away from each other so as to retain said wire in said slots and with said portions behind said

tongues, said spring wire being bowed away from said frame member between said apex and the ends thereof.

2. A rack for holding articles such as a book, a newspaper, clippings, a card or sheet of paper in such a manner that printed matter thereon is visible to an observer looking downwardly or forwardly thereat comprising a frame member providing a laterally extending supporting surface, means for supporting said member so that said surface is arranged upright and means for retaining an article of the nature hereinbefore referred to upon said supporting surface comprising a curved inverted U-shaped spring wire, the ends of which are secured to said frame member adjacent the lower corners thereof, an intermediate portion of said wire at the top thereof being formed to provide an upwardly projecting point which is biased toward said surface so as to contact an article at a point spaced above the ends of said wire and removably clamp said article to said surface of said frame member, horizontally spaced parts of said spring wire adjacent the ends thereof being formed to provide spaced seats arranged laterally on each side of said intermediate portion for an article clamped thereby to said surface, said spring between each of said ends and said point thereof being curved away from and back toward said surface, said spring wire extending downwardly and outwardly from said point and away from said surface.
